UNITED STATES PATENT OFFICE.

OSCAR J. ZIEGLER, OF RIVER ROUGE, MICHIGAN.

APPARATUS FOR TREATING ORE.

1,377,542.

Specification of Letters Patent. Patented May 10, 1921.

Application filed October 20, 1919. Serial No. 331,806.

To all whom it may concern:

Be it known that I, OSCAR J. ZIEGLER, a citizen of the United States, and resident of River Rouge, in the county of Wayne and 5 State of Michigan, have invented certain new and useful Improvements in Apparatus for Treating Ore; and I do hereby declare that the following is a full, clear, and exact description thereof.

10 This invention relates to new and useful improvements in apparatus for treating ore, and is primarily designed for use in cyanid- ing processes in the separation of gold and silver from their ores.

15 Heretofore it has been customary in these processes to cause the ore pulp and cyanid solution to travel down a continuous incline, or to be elevated step by step with relatively little agitation. Inasmuch as a much more 20 efficient action of the cyanid solution may be obtained by thoroughly agitating and aerat- ing the pulp with the solution, it is the prin- cipal object of the present invention to pro- 25 vide an arrangement for successively elevat- ing the pulp and cyanid solution from one receiving receptacle of a series and dump- ing the same into another receptacle of the same or an additional series.

30 A further object is to provide an appara- tuss of this character which is composed of one or more agitating and aerating units, which, in case several are used, may be com- bined in various relationships. For instance 35 the several units can be positioned horizon- tally with respect to each other, or verti- cally, or at an incline, or in a combination of these various arrangements. Furthermore 40 in view of such a feature an apparatus may be readily built up to accommodate any amount of ore pulp and readily increased 45 in capacity when the amount of the latter increases.

50 Still another object is to provide an agitating and aerating unit for treating apparatus which can be easily varied as to capacity by changing the number of pulp and cyanid solution receiving receptacles.

With these general objects in view, the in- 55 vention resides in the novel features of con- struction, combination and arrangement of parts which will be hereinafter more par- ticularly described and claimed.

In the accompanying drawings, Figure 1 60 represents a front elevational view of an

aerating and agitating unit for ore treating 55 apparatus.

Fig. 2 is a side elevational view, partly in section, of the unit shown in Fig. 1.

Fig. 3 is a diagrammatic view showing the association of several aerating and agitating 60 units to indicate the manner in which they may be associated, and

Fig. 4 is a sectional view through a pair of pulp and solution receiving receptacles showing one manner of associating the con- 65veying and agitating mechanism therewith.

Referring now more particularly to the drawings, it will be seen that each of the agitating and aerating units U which go to make up an ore treating apparatus is con- 70structed in substantially the same manner and operated similarly, although each may be different as regards capacity and specific arrangement of parts. It will therefore be appreciated that the invention does not con- 75sist in the construction and arrangement of parts illustrated, but in any general arrangement embodying the same features and methods of operation.

The units U shown in Figs. 1 and 2 con- 80sist of a supporting frame comprising pref- erably angle metal corner bars 1, upper and lower transverse brace bars 2 and 3, and in- 85termidiate supporting bars 4 and 5, the lat- ter being horizontally and alternately dis- posed and vertically spaced. Each of the supporting bars 4 and 5 mounts one or more 90bearings 6 in which sprocket shafts 7 are journaled, and in addition the supporting bars 5 have one or more ore pulp and cyanid 95solution receiving receptacles 8 secured thereto by their opposite ends.

When more than one of the receiving 100receptacles 8 is mounted between each cor- responding pair of supporting bars 5, they are arranged parallel to each other and in close proximity so that the opposite longi- 105tudinal edges thereof abut as indicated in Fig. 2 and in the diagrammatic Fig. 3. Furthermore each series of receptacles thus formed is positioned substantially horizont- ally. The units illustrated are of com- paratively small capacity, and therefore only a pair of receptacles is used in each of the horizontal series with the exception of the lowermost which contains three re- 110ceptacles. However, each series may con- tain any number of receptacles, and if de-

sired, instead of having the series vertically superposed as shown, a like number of receptacles may be positioned in one horizontal line, the amount of agitating and aerating of the receptacle contents being approximately similar in either case.

Disposed on the sprocket shafts 7 journaled in the bearings carried by the several bars 2, 4 and 5, are sprockets, two being secured to each shaft. Hereafter the several types of sprockets will be designated in accordance with their function as filling sprockets 9, dumping sprockets 10 and guide sprockets 11. It will be noted that the filling sprockets are mounted on the shafts 7 journaled in the bearings on the supporting bars 5 and are located within the receptacles 8, one being disposed adjacent each end of each of the receptacles, whereas the dumping sprockets are disposed over the receptacles 8.

As will be seen from Fig. 1, two sets of sprockets are employed, one being adjacent each end of the receptacles 8, and around each of the sets is trained an endless link belt or chain 12. The two link belts are connected by a plurality of relatively shallow buckets 13. In practice these buckets may be of any appropriate length, but are preferably so spaced apart that there will be five in each foot of belt. The teeth of the sprockets 9, 10 and 11 engage in openings in the link belts 12 and cause the same to travel into and out of the several receptacles, the buckets 13 thus successively removing the ore pulp and cyanid solution from one receptacle and dumping it into another. Thus in the structure illustrated in Figs. 1 and 2 the link belts 12 and their buckets 13 pass beneath the sprockets 9 and over the sprockets 10, the other sprockets 11 being arranged in suitable positions to guide the belts. The pulp and cyanid solution is very thoroughly agitated and aerated by being caused to drop a considerable distance from the buckets 13 as they pass over each pair of dumping sprockets and into the receptacle therebelow. This drop need not be very considerable in view of the fact that the pulp and solution is continuously acted upon in this manner throughout the passage of the same from the first receptacle of the first unit to the last receptacle of the last unit.

In the form of the invention shown in Figs. 1, 2 and 3 the sprocket shafts of the dumping sprockets 10 are in vertical planes within the receptacles into which the buckets passing around their respective sprockets are caused to discharge. In other words the vertical planes of these shafts of the sprockets 10 are disposed inwardly of the forward edges of the receptacles into which the buckets passing therearound are designed to dump, thus any pulp and solution removed

by the buckets from one receptacle cannot be discharged back into the same receptacle, but must fall into the receptacle next in the series. However, in the form illustrated in Fig. 4 the vertical planes of the shafts of the dumping sprockets are directly over the abutting edges of the receptacles 8 so that a deflector plate 15 is secured to the abutting edges so that the pulp and cyanid solution cannot fall back into the same receptacle from which it has just been removed by the buckets 13.

From Fig. 3 it will be appreciated that various arrangements may be employed by transferring the pulp and solution from one of the units *U* to the other, for instance between the units *a* and *b*, the pulp and solution may flow by gravity from one of the receptacles 8 of the uppermost series of the first unit through a chute or the like 16 to one of the receptacles of the lowermost series of the other unit. In the unit *c* the pulp and cyanid solution is received from the unit *b* in a supplemental receptacle 17, from which it is elevated to the first receiving receptacle of the lowermost series. The initial receiving arrangement of the other unit *d* is substantially the same, in the present case, to the unit *c*.

With an ore treating apparatus of this character the location of the stamp mills is immaterial, as the several units may be assembled in practically any relationship. If space is limited the units may be positioned substantially vertically, whereas on the other hand if the plant may be spread out, or if climatic conditions prevent the association of the units in the form of a tower, they may be disposed substantially horizontally or in stepped relation.

I claim:

1. An ore treating apparatus unit comprising a pair of pulp and solution receptacles, one being an initial receiving receptacle and the other a secondary receiving receptacle, a guide disposed adjacent the initial receptacle, another guide located over the secondary receiving receptacle, an endless conveyer trained about the guides and removing the contents from the initial receptacle and dumping them into the secondary receiving receptacle, and intermediate guides for directing the conveyer about the other guides.

2. An ore treating apparatus unit comprising a pair of pulp and solution receptacles, one being an initial receiving receptacle and the other a secondary receiving receptacle, and a second pair of pulp and solution receptacles disposed above the first pair of receptacles, one receptacle of said second pair also being an initial receiving receptacle and the other a secondary receiving receptacle, a guide disposed adjacent each initial receptacle, another guide located over

each secondary receiving receptacle, an endless conveyer trained about the guides and removing the contents from the initial receptacle of the first pair and dumping it 5 into the secondary receiving receptacle of said first pair and then elevating the receptacle contents from said secondary receiving receptacle of the first pair to the initial receiving receptacle of the second pair, said 10 conveyer removing the contents from the initial receptacle of the second pair and dumping it into the secondary receiving receptacle of said second pair of receptacles, and intermediate guides for directing the 15 conveyer about the other guides.

3. An ore treating apparatus unit comprising a pair of pulp and solution receptacles, one being an initial receiving receptacle and the other a secondary receiving receptacle, a filling wheel disposed in each of 20 the receptacles, a dumping wheel disposed above the receptacles, an endless conveyer disposed below the filling wheels and above the dumping wheel whereby to remove the 25 contents from the initial receiving receptacle and dumping it into the secondary re-

ceiving receptacle, and intermediate guide wheels for directing the conveyer about the other wheels.

4. An ore treating apparatus unit comprising a pair of pulp and solution receptacles, one being an initial receiving receptacle and the other a secondary receiving receptacle, a filling wheel disposed in each of the receptacles, a dumping wheel disposed above the receptacles, the center of the dumping wheel being in a vertical plane within the sides of the secondary receiving receptacle, and an endless conveyer disposed below the filling wheels and above the dumping 30 wheel whereby to remove the contents from the initial receiving receptacle and dumping it into the secondary receiving receptacle, and intermediate guide wheels for directing the conveyer about the other 35 wheels.

In testimony that I claim the foregoing I have hereunto set my hand at River Rouge in the county of Wayne and State of Michigan.

OSCAR J. ZIEGLER.
